RADIO CLOCK

Russell Bernstein, Chicago, Ill.

Application April 27, 1949, Serial No. 2,303

Term of patent 7 years

(Cl. D42—7)

To all whom it may concern:

Be it known that I, Russell Bernstein, a citizen of the United States and resident of Chicago, in the county of Cook and State of Illinois, have invented a new, original, and ornamental Design for a Radio Clock, of which the following is a specification, reference being had to the accompanying drawing, forming a part thereof.

Fig. 1 is a top plan view of a radio clock showing my new design.

Fig. 2 is a front elevational view thereof.

Fig. 3 is an elevational view of the right hand side of the radio clock as viewed in Fig. 2.

Fig. 4 is an elevational view of the left hand side of the radio clock as viewed in Fig. 2.

I claim:

The ornamental design for a radio clock, substantially as shown.

RUSSELL BERNSTEIN.
